United States Patent Office

Des. 190,853

Patented July 11, 1961

190,853

LIFT TRUCK

Sigmon R. Neville, 1008 Chevy Chase Drive,
Angleton, Tex.

Filed June 27, 1960, Ser. No. 61,115

Term of patent 14 years

(Cl. D14—3)

FIG. 1

FIG. 2

FIG. 1 is an isometric view of a lift truck showing my new design; and

FIG. 2 is a rear elevational view thereof.

The side not shown is substantially the same as the side shown.

I claim:

The ornamental design for a lift truck, as shown and described.
